Attorney

UNITED STATES PATENT OFFICE.

ART HADLEY, OF PROVIDENCE, RHODE ISLAND, ASSIGNOR TO THE HADLEY COMPANY,
OF PROVIDENCE, RHODE ISLAND.

MEANS FOR SECURING ROWS OF PEARLS OR THE LIKE.

Application filed August 6, 1926. Serial No. 127,609.

This invention relates to certain new and useful improvements in means for securing rows of pearls or the like, and the primary object thereof is to provide improved means 5 for securing rows or strands of pearls, beads, ornaments or the like onto an attaching member.

A further object of the invention is to provide means of the type set forth, which 10 is of simple and economical construction, and which enables the pearls or the like to be easily and quickly secured onto an attaching member and effectively held in position, without the use of extraneous or mov- 15 able fastenings.

In the drawings:—

Fig. 1 is a plan view of the invention;

Fig. 2 is a section on line 2—2 of Fig. 1.

Fig. 3 is a detail view of the attaching 20 ear of an end hook for wrist watch bracelets, in connection with which latter the invention is illustrated by way of example;

Fig. 4 is a section on line 4—4 of Fig. 1 and

Fig. 5 is a detail perspective view of the attaching bar.

In proceeding in accordance with the present invention, a bar body 1 is provided which has cylindrical pintles 2 at its ends, 30 the bar being formed of a sheet or plate of metal rolled, bent or curled into tubular form to provide pintles 2 and radial lips 3. The body is laterally perforated at 4 according to the number of strands of pearls 35 5 that are to be secured. The pearls or other ornaments are threaded or strung on silk threads or chains 6 and the free ends of the latter are then passed through the perforations or passages 4 so as to lie within the body and between the lips whereupon the 40 lips are pinched or compressed so as to frictionally grip the threads 6 and thus firmly secure or anchor the threads to the bar.

In the drawings, an end hook 7 having

bendable ears is illustrated in connection 45 with one use to which the invention may be put, the ears being first spread to align the pintles 2 with their perforations, following which the ears are bent into the position 50 illustrated in the drawings, thus supporting 50 the pintles for free pivotal movement.

From the foregoing, it will be seen that no movable or extraneous parts, are em- 55 ployed in securing the strands or pearls or the like to the lips 3, and while the latter is shown attached to an end hook, it will be understood that such illustration is purely by way of example.

Having thus described my invention what I claim as new and desire to secure by Let- 60 ters Patent is:—

1. A connector for strings of pearls and the like composed of a hollow bar having a laterally perforated body, a pair of lips extending outwardly from the body, and strings having pearls thereon and having one end passed through the perforations and received between the lips, the lips being com- 65 mon to all of the strings and compressed to frictionally and simultaneously engage and hold all of said string ends therebetween.

2. A connector for strings of ornaments composed of a hollow body having a series of perforations along a side thereof, and having a pair of spaced opposed parts at 75 the opposite side of the body and with the space between said parts aligned with the perforations, and ornament-carrying strings having one end thereof extending through the perforations and received in the space 80 between said parts, said parts being common to all of the strings and being compressed to frictionally and simultaneously engage and hold all of the string ends therebetween.

In testimony whereof I have signed my 85 name to this specification.

ART HADLEY.
